MULTIPLE CAVITY RESONATOR

Lothar Brück, Paris, France, assignor to Compagnie Générale de Télégraphie Sans Fil, a corporation of France

Application August 24, 1948, Serial No. 45,855
In France August 28, 1947

7 Claims. (Cl. 315—5)

1

The present invention relates to a multiple cavity resonator of a type which may be used to particular advantage in a klystron of the reflex type.

According to one feature of the invention, the said resonator is provided with a plurality of re-entrant portions which may be mutually coupled by loops known as "strappings."

For the purpose of establishing a klystron of great power, it is known to locate a plurality of electronic systems in mutual proximity inside the same tube. The resonator circuit (or circuits) is then constituted by a cavity with a plurality of re-entrant portions. The maximum electrical field corresponding to the required wave is always found at the summits of the re-entrant portions. A large cavity of this nature may be considered as being partitioned by the walls of each re-entrant portion and divided into a plurality of small cavities which are mutually coupled by their magnetic fields. The fields of adjacent cavities are opposed in phase, but there are many cases where this method of coupling is too loose. If the coupling could be tightened, on the one hand the required wave could be advantageously discriminated from the parasite or disturbance waves (and it is known that there are several such waves in a klystron having a multiple cathode associated with a multiple cavity), and it would be very much easier to change the resonance frequency. Furthermore, the output efficiency of the tube would be improved.

One object of the invention is to provide coupling means for multiple cavity resonators whereby these advantages are achieved and the elemental cavities are more tightly coupled to each other.

Another object is to provide a multiple cavity resonator equipped with a device for coupling the elemental cavities thereof.

In the accompanying drawing:

Figure 1 shows a multiple cavity seen in perspective, part of the wall having been removed to give a view of the inside of the cavity;

Figure 2 is a plane view of the cavity of Figure 1;

Figures 3 and 4 are plan views of cavities with different coupling devices;

Figure 5 is a longitudinal section in a radial plane of the cavity and tuning system;

Figure 6 is a plan view of a cavity with a larger number of elemental cavities;

Figure 7 is a plan view of a cavity with capacitive coupling;

2

Figure 8 is a view similar to Figure 5 but of the device of Figure 7;

Figure 9 is a partial view in perspective showing the arrangement of a cavity according to the invention inside a klystron tube.

In Figure 1, a cavity K comprises re-entrant portions 1 to 6 which are arranged in a circle, as seen also in Figure 2, and which define elemental cavities. In the vicinity of each re-entrant portion is arranged a coupling loop or strapping and connections are established between the loops located near cavities of same phase. Figures 1 and 2 show an arrangement of 6 re-entrant portions. At all times the cavities near elements 1—3—5 are of same phase as also those near elements 2—4—6 in opposition thereto. By means of loops or strappings S₁ and S₂ the cavities at 1—3—5 and at 2—4—6 are respectively coupled. Without these loops, the cavity at 3 would be coupled only to the adjacent cavities at 2 and 4. But with the loop, it is coupled also to the cavities at 1 and at 5. Hence the total coupling of the cavities is considerably tighter.

According to the desired rate of coupling, it is possible to use only one coupling star S₁ or two stars S₁ and S₂ coupled together. For example, only the cavities occupying even-numbered positions may be coupled.

Instead of coupling stars, triangles may be used, either one or two, as shown by S₁ and S₂ in Figure 3, where the apices of one triangle are located all in even-numbered or all in odd-numbered cavities.

In the device of Figure 4, one set of cavities is coupled by a triangle, and the other set by a star, but here the coupling between the strappings is looser than in Figures 1 to 3.

With the type of coupling so far described, it is possible to obtain a good flow of decimetric energy as well as greater ease of frequency variation. Figure 5 shows one example of construction wherein a group of cavities including the one near element 4 is coupled by a triangle or star S₂ visible on Figures 1 to 4 but not shown on Figure 5. The cavities of the other group including the one near element 1 are coupled together by a star, the center of which is connected to the interior lead of a coaxial line L. The flow of energy occurs simultaneously from all three elemental cavities. By means of piston K, the line may be adapted to any desired impedance which is then communicated as a parallel impedance in the elemental cavities through the branches of coupling star

S1. In this manner, the cavities can be tuned and their resonance changed. This coupling device adds a variable impedance to one out of two elemental cavities, and the range of possible frequency variation is greater than with a coupling involving only one elemental cavity.

Obviously this type of coupling is not limited to six re-entrant portions and can be used with 4, 8, 12, etc., and where there are 8 or more elemental cavities, the coupling can be either polygonal as in Figure 6 or by stars with interconnected points as in Figure 7.

It is also possible to use capacitive instead of inductive coupling. In this case, instead of the coupling loops comprising curved ends coupled inductively to the cavities, the device comprises, for the purpose of coupling, only the single capacity existing between the respective surfaces of the loops and of the cavities. In Figure 8, which corresponds, for the sake of example, to a section of Figure 7, there is shown a single loop S1 supported by an insulator i. The power outlet can, for example, be extracted through axial line L passing through insulator i. Figure 9 shows a partial view of a device, according to the invention, incorporated in a reflex klystron seen in perspective and broken away through the center. This type of klystron is known as "multi-canon." Re-entrant portions 1, 5, 4 and 6 are clearly shown to have a conical shape since the strict cylindrical shape is not necessary for the purpose of the invention. Cathodes C are heated by filaments f, and there are provided reflecting electrodes R, the whole device being contained in an envelope E. Loop S1 is connected to concentric line L for the purpose of extracting energy.

It will be understood that the embodiments described are given by way of illustrative example and that it is not the purpose of this description to limit the invention, which is fully covered by the scope of the appended claims.

What I claim is:

1. Electronic tube for ultra high frequency and super high frequency comprising at least one cavity resonator in the form of a hollow body bounded by a surface comprising a plurality of re-entrant portions dividing the interior of the cavity into partial cavities, means for causing an electronic beam to traverse each re-entrant portion, means for producing fields of different phases in the partial cavities, a first coupling member having integral portions extending into proximity to a first group of partial cavities in which fields of the same phase are produced, and a second coupling member having integral portions extending into proximity to a second group of partial cavities in which fields of the same phase are produced out of phase with respect to the fields produced in said first group of partial cavities, thereby inductively coupling together those partial cavities in which fields of the same phase are produced.

2. Electronic tube for ultra high frequency and super high frequency comprising at least one cavity resonator in the shape of a hollow body

bounded by a surface comprising a plurality of re-entrant portions dividing the interior of the cavity into partial cavities, means for causing an electronic beam to traverse each re-entrant portion, means for producing fields of different phases in the partial cavities, means inductively coupling together a first group of partial cavities in which the field is of one phase, means inductively coupling together a further group of partial cavities in which the field is of same phase, different from that of said first group, and means inductively coupling together both said coupling means.

3. Electronic tube for ultra high frequency and super high frequency comprising at least one cavity resonator in the shape of a hollow body bounded by a surface comprising a plurality of re-entrant portions dividing the interior of the cavity into partial cavities, means for causing an electronic beam to traverse each re-entrant portion, means for producing fields of different phases in the partial cavities, means inductively coupling together those partial cavities in which the field is of the same phase, and means for extracting energy from the tube, said last named means being inductively coupled to said coupling means.

4. A tube according to claim 1 wherein at least one of the coupling members comprises a metallic part in the form of a star having a plurality of branches, extending as far as the related partial cavities, having fields of the same phase.

5. Tube, according to claim 1, wherein at least one of the coupling members comprises a metallic part in the shape of a polygon, the sides of which traverse the partial cavities having fields of the same phase.

6. A tube, according to claim 1, wherein at least one of the coupling members comprises a metallic part in the shape of a star having a plurality of points extending as far as the related partial cavities having fields of the same phase, the ends of the points of the star being interconnected by metallic connecting pieces.

7. Electronic tube for ultra high frequency and super high frequency according to claim 1; wherein each of said integral portions of the first and second coupling members consists of a curved metal part extending into the related partial cavity.
